SELF-CLEANING MAGNETIC SWITCH

George Wintriss, Carversville, Pa., assignor to Industrionics Controls, Inc., New York, N.Y., a corporation of New York

Filed Mar. 26, 1965, Ser. No. 442,887

15 Claims. (Cl. 200—87)

This invention relates to electric switches and more especially to improvements in magnetic switches.

It is an object of this invention to provide a magnetic switch having a movable contact formed so that there is a self-cleaning action at the points of contact.

It is another object of this invention to provide improved magnetic switches operating with a snap action that has no pre-travel.

Some other features of the invention relate to a versatile combination of fixed contacts and a movable contact, utilizing at least two magnets, to provide a self-cleaning magnetic switch which may function as a single pole-double throw switch, a momentary open switch, or a momentary break switch, dependent upon the electrical connections made to two of three fixed contacts in the switch mechanism.

Other objects, features and advantages of the invention will appear or be pointed out as the description proceeds.

In the drawings, forming a part hereof, in which like reference characters indicate corresponding parts in all the views:

FIGURE 1 is a perspective view of an electrical switch made in accordance with this invention enclosed in the switch housing;

FIGURE 2 is a perspective view of the switch shown in FIGURE 1 with the two halves of the housing separated whereby the switch mechanism is shown;

FIGURE 3 is a sectional view taken on lines 3—3 of FIGURE 1;

FIGURE 4 is a diagrammatic sectional view taken along lines 4—4 of FIGURE 1; and

FIGURE 5 is a diagrammatic view showing a modified form of the switch which may be enclosed in a housing such as that shown in FIGURE 1.

FIGURES 1, 2 and 3 show a switch 20 composed of a housing having a lower portion 21 and an upper portion 22. The housing has an upper side 23, and a lower side 24. The upper portion 22 and the lower portion 21 of housing encloses a chamber for a switch mechanism composed of three substantially parallel contact bars 34, 38 and 40 connected to the side walls, and a round movable contact bar 35. Plunger 32 extends into the switch chamber.

The switch shown is a single pole, double throw switch. Contact bar 34 is electrically connected to an external wire 28. Contact bar 34 which is connected to the lower portion 21 is a permanent magnet which attracts the round movable contact bar 35 and acts as the single pole of the switch. Round contact bar 35 is made of a para-magnetic material and has a necked portion 36 in contact with bar 34. The other end of the contact bar 35 is normally in contact with the contact bar 40 which is also a permanent magnet. The contact bar 40 is connected to the upper portion 22 and is in electrical contact with an external wire 29. In the switch mechanism's normally closed position, an electric circuit is formed between contact 34, contact bar 35, and contact 40.

The inner mating faces 25 and 26, respectively, of the upper and lower portions of the switch housing contain an annular opening 43, one-half of which is illustrated in FIGURE 2, to provide space for a plunger 32 which extends outwardly from the front faces 30 and 31 of the housing. Plunger 32 extends into the switch

2

mechanism, terminating in an annular lip 33 which is normally in contact with a movable contact bar 35 when the bar 35 touches a contact bar 40.

When the plunger 32 is resting in contact with the round contact bar 35 and the contact bar is against the magnetic contacts 34 and 40, the switch is in its normal closed circuit position.

When pressure is applied to the plunger 32, the force against the round contact bar 35 increases until it is sufficient to overcome the attraction of the magnetic contact 40 for the round bar 35. The round bar 35 then moves away from the magnetic contact 40 with a snap action which results from the rapid decrease in the magnetic attraction as the air gap between the magnetic contact 40 and the round bar 35 increases. This produces the snap action. The application of pressure on plunger 32 (in contact with bar 35) causes breaking of the contact between magnetic contact 40 and the round contact bar 35 without any pre-travel of the plunger 32.

When the plunger 32 has been depressed and sufficient pressure applied to break the contact between the round contact bar 35 and the contact 40, the round contact bar 35 pivots about the contact 34 as a fulcrum and is thrust into contact with the electrical contact 38. The electrical contact 38 is not a magnet. It is connected to the housing portion 21 and is in electrical contact with the external wire 27.

The movement of the round bar 35 into contact with the contact 38 closes an electrical circuit between the contacts 38 and 34 through the round bar 35. This circuit continues closed so long as pressure is applied upon the plunger 32. When pressure on the plunger 32 is released, the round contact bar 35 snaps back into contact with the magnetic contact 40. This movement is caused by the magnetic attraction of the contact 40 for the round bar 35.

FIGURE 4 illustrates the electrical connections of the contacts to the external wires. Contact 40 is connected with the external wire 29 through a terminal 41. Contact 38 is connected to an external wire 27 through a terminal 42. Contact 34 which is not illustrated in FIGURE 4 is connected to the external wire 28 through a terminal in a manner similar to the connections between the contact 38 and the wire 27.

It is a particular advantage of the switch mechanism of this invention that when the round movable bar 35 is moved under pressure of plunger 32 out of contact with magnetic contact 40, there is some rotational movement of the round bar 35 about its longitudinal axis. There is similar rotational movement of said bar 35 when it moves away from contact 38 and returns to the closed-circuit position in contact with the magnetic contact 40. This rotational movement of the round contact bar 35 causes contact with the permanent contact 34 to be made at different points around the periphery of the necked portion 36 of the bar 35. Similarly, the peripheral point of contact of the other end of the bar 35 with the contacts 40 and 38, respectively, are changed with each movement of the switch. This imparts a wiping and self-cleaning action to the contacts at the points where arcing may occur.

To accentuate the rotational movement of the round movable bar 35, it is preferred that the pressure applied by the plunger 32 to the bar 35, should be applied against the bar 35 in a non-radial direction, thereby creating a moment about the longitudinal axis of the bar 35.

Although the switch mechanism has been described in connection with a single pole, double throw switch, it is apparent that relatively minor modifications result in the same mechanism being useful as a momentary contact switch, or a momentary break switch.

A momentary contact switch results when the permanent magnet 40 is not an electrical contact so that it is

not part of an electric circuit. The switch in the normal position having the movable bar 35 contacting the permanent magnet 34 and the permanent magnet 40 is in an open circuit position. Movement of the plunger 32 will cause the round movable bar 35 to break away from the magnet 40 and touch the electric contact 38 thereby forming a closed circuit between the contacts 34 and 38 through the movable contact 35. This circuit will remain closed so long as pressure is maintained on the plunger 32. When pressure is released, the circuit is immediately broken by the attraction of the permanent magnet 40 for the movable contact 35 and the switch returns to the normally open position.

The switch operates as a momentary break switch when the bar 38 is not an electrical contact. It functions only as an abutment. The switch is normally closed forming an electric circuit between the contacts 34 and 40 through the movable bar 35. Application of pressure by plunger 32 breaks the circuit by moving the bar 35 against the abutment 38.

FIGURE 5 shows a modification of the invention in which the three stationary electrical contacts 101, 102 and 103 are each permanent magnets. A round movable contact bar 104 has a neck portion 105 at one end adjacent the contact 103 and another neck portion 106 at the other end adjacent and between the contacts 101 and 102. The neck portion 106, of the round contact bar 104 which is made of paramagnetic material, is attracted to both magnetic contacts 101 and 102 and will move into contact with whichever of said contacts 101 and 102 it is closest to at any given time.

When the neck portion 106 touches the magnetic contact 101, or magnetic contact 102, it will remain in contact therewith until forced away by a plunger 107 or 108. In one closed position of the switch, the round contact bar 104 closes a circuit between contacts 102 and 103. When the plunger 107 is moved against the movable bar 104, the bar 104 pivots about the contact 103 and moves away from the contact 102, into the magnetic field of the contact 101 and immediately into snap contact with the contact 101, thereby forming a closed circuit between contacts 101 and 103 through the round contact bar 104.

To return the switch mechanism to the position wherein a closed circuit is effected between contacts 102 and 103 through the round contact bar 104, pressure is applied by a plunger 108 which causes movable bar 104 to pivot about a fulcrum 109 away from magnetic contact 101 into the field of superior magnetic attraction of contact 102 and into snap contact with the contact 102. The sequence of movements involves pressure by the plunger 108 against round contact bar 104, causing said bar 104 to move away from contact 103 until said movement is stopped by peripheral contact of bar 104 with fulcrum 109. Continued pressure by plunger 108 then causes the movable bar 104 to pivot on the fulcrum 109 whereby the neck portion 106 is moved away from the contact 101 into the magnetic field of the contact 102 and then into physical contact with the contact 102. The plunger 108 is then released whereby the neck portion 105 of the bar 104 is snapped back into contact with the contact 103 by the magnetic attraction of the contact 103.

The switch mechanism utilizing the three permanent magnets 101, 102 and 103 may be operated with only the plunger 107. When a circuit is closed between the contacts 102 and 103 through the round bar 104, pressure on the plunger 107 sufficient to break the contact between the contact 102 and the neck portion 106 of the round bar 104 will bring the neck portion 106 into snap contact with the contact 101. Additional pressure on the plunger 107 will cause the bar 104 to pivot about the fulcrum 109, thereby moving bar 104 away from the contact 101 and back into snap contact with the contact 102. Release of pressure on the plunger 107 results in the return of the neck portion 105 of the bar 104 into contact with the contact 103.

5 The round movable bars 35 and 104 of this invention are of a paramagnetic material and preferably a ferrous alloy. The non-magnetic electrical contact 38 may be constructed of similar material. Contacts 34, 40, 101, 102 and 103 are all constructed of permanent magnetic materials. The surfaces of all these contacts, particularly those portions that actually make electrical contact may be faced with silver or some other non-ferrous material which is particularly well suited for electrical contacts. In such a case, the contacts may be considered as of composite construction.

10 The preferred embodiment and a number of modifications of the invention have been illustrated and described, but changes and other modifications can be made and features of the invention can be used in different combinations without departing from the invention as defined in the claims.

15 What is claimed is:

20 1. A self-cleaning magnetic switch including a round movable contact bar made of para-magnetic material held in electrical contact at one end by a magnetic contact that serves as a fulcrum for said round bar, and adjacent opposite sides of the other end of said round movable bar, a magnetic abutment and a second abutment, at least one of said abutments also being an electric contact, whereby said round bar is positioned having one end in contact with said magnetic contact and the other end in contact with said magnetic abutment, and a plunger positioned on the side of said round bar which is adjacent said magnetic abutment at a position intermediate the ends of said round bar whereby movement of said plunger against said round bar thrusts said round bar away from said magnetic abutment with a snap action and against said second abutment.

25 2. A self-cleaning magnetic switch including a movable round contact bar made of para-magnetic material held in electric contact at one end by a first magnetic contact that serves as a fulcrum for said round bar and a second magnetic contact adjacent the other end of said movable bar whereby an electric circuit is formed between said two magnetic contacts and said round bar, and a plunger positioned on the side of said round bar which is adjacent said second magnetic contact at a position intermediate the ends of said round bar whereby movement of said plunger against said round bar thrusts said round bar away from said second magnetic contact with a snap action, and abutment means limiting the movement of said movable bar away from the magnet to a distance less than the effective range of the attraction of said magnetic contact.

30 3. A self-cleaning magnetic switch including a round movable contact bar made of para-magnetic material held in electric contact at one end by a magnetic contact that serves as a fulcrum for said round bar, and a magnetic abutment adjacent one side of the other end of said round bar, and an electric contact adjacent the side of said round bar opposite that adjacent to said magnetic abutment, whereby said round bar is positioned having one end in contact with said magnetic contact and the other end in contact with said magnetic abutment, and a plunger positioned on the side of said round bar which is adjacent said magnetic abutment at a position intermediate the ends of said round bar whereby movement of said plunger against said round bar thrusts said round bar away from said magnetic abutment with a snap action and into contact with said electric contact whereby an electric circuit is formed between said magnetic contact through said round bar which continues only so long as pressure is applied to said plunger.

35 4. A single pole, double throw self-cleaning switch including a round contact bar made of para-magnetic material held in electric contact at one end by a first magnetic contact that serves as a fulcrum for said bar, and a pair of electric contacts adjacent opposite sides of the other end of said bar, one of said contacts being a non-

magnetic contact and the other of said contacts being a second magnetic contact which attracts said bar whereby an electric circuit is formed between said two magnetic contacts through said round bar, and a plunger positioned on the side of said bar which is adjacent said second magnetic contact at a location intermediate the ends of said bar, whereby movement of said plunger against said round bar thrusts said round bar away from second magnetic contact with a snap action and into contact with said non-magnetic electric contact thereby forming a circuit between said first magnetic contact and said non-magnetic electric contact through said round bar.

5. The switch of claim 4 characterized by having the plunger positioned against said round movable bar, guide means in which the plunger moves in a direction to thrust the round bar away from said second magnetic contact with a snap action and to impart a rotative movement to said round bar, whereby the bar has a self-cleaning action.

6. The switch described in claim 4, characterized by a round contact bar having a necked portion in contact with said first magnetic contact.

7. The switch described in claim 5, characterized by said first magnetic contact being a cylindrical bar having its axis substantially normal to a plane through the axis of said round contact bar.

8. The switch of claim 7 characterized by having the plunger positioned against said round movable bar, guide means in which the plunger moves in a direction to thrust the round bar away from said second magnetic contact with a snap action and to impart a rotative movement to said round bar, whereby the bar has a self-cleaning action.

9. A self-cleaning switch having a housing in which the switch is enclosed in a chamber defined between an upper and a lower portion of said housing, said switch having a first round magnetic contact bar connected to one side of said housing with its axis normal to the plane of said side, a round movable contact made of para-magnetic material held in electrical contact at one end by said first magnetic contact, an electric contact connected to the same side of the housing as said first magnetic contact and substantially parallel to said first magnetic contact positioned toward the opposite end of said round movable bar, and a second magnetic contact positioned across said round bar from said electric contact, said second magnetic contact being connected to the side of the housing opposite to the side to which the first magnetic contact is connected and having its axis normal to the plane of the side of the housing to which it is connected, said round movable bar being normally in contact with said first and second magnetic contacts whereby an electric circuit is formed, and a plunger having one end positioned on the side of said round bar which is adjacent said second magnetic contact at a position intermediate the ends of said round bar, said plunger having its other end extending outwardly through the wall of said housing, whereby movement of said plunger against said round bar thrusts

said round bar away from said second magnetic contact with a snap action and into contact with said electric contact thereby forming a circuit between said first magnetic contact and said electric contact through said round bar.

10. The switch of claim 9 characterized by having the plunger positioned against said round movable bar, guide means in which the plunger moves in a direction to thrust the round bar away from said second magnetic contact with a snap action and to impart a rotative movement to said round bar, whereby the bar has a self-cleaning action.

11. The switch described in claim 9 characterized by said electric contact being positioned on the same side of said round bar as said first magnetic contact.

15. 12. The switch described in claim 11 characterized by a round contact bar having a necked portion in contact with said first magnetic contact.

13. The switch of claim 12 characterized by having the plunger positioned against said round movable bar, 20 guide means in which the plunger moves in a direction to thrust the round bar away from said second magnetic contact with a snap action and to impart a rotative movement to said round bar, whereby the bar has a self-cleaning action.

25. 14. An electric switch including a round movable contact bar with end portions that constitute electric contacts of the circuit of the switch, two electric contacts above said round bar and each of which is adjacent to a different end portion of said round bar, each of said two electric

30 contacts being a magnet, another magnetic electric contact below the upper electric contact at one end of said round bar, two plungers at spaced locations along the length of said round bar and between the two upper electric contacts, and a fulcrum under said round bar and

35 nearer to the end of said round bar having the electric contacts both above and below said round bar, said fulcrum being at least as low as the lower periphery of said round bar when said round bar is in contact with the lower electric contact at the other end of said round

40 bar, one of the plungers contacting with said round bar beyond the fulcrum on the side of the fulcrum away from the end of said round bar that has electric contacts both above and below it, and characterized by having the plunger positioned against said round bar, guide means

45 in which the plunger moves in a direction to thrust the round bar away from the second magnetic contact with a snap action and to impart a rotative movement to said round bar, whereby the bar has a self-cleaning action.

15. The switch described in claim 14 characterized by 50 having the ends of said round bar adjacent said electric contacts of reduced diameter thereby forming a neck to facilitate the pivotal contact between said round bar and said electric contacts.
